UNITED STATES PATENT OFFICE.

FRANK SCHILZ, OF MILWAUKEE, WISCONSIN.

MATCH-PACKAGE.

SPECIFICATION forming part of Letters Patent No. 397,756, dated February 12, 1889.

Application filed August 23, 1888. Serial No. 283,589. (No model.)

To all whom it may concern:

Be it known that I, FRANK SCHILZ, of Milwaukee, in the county of Milwaukee and State of Wisconsin, have invented certain new and 5 useful Improvements in Match-Packages, of which the following is a specification.

The object of my invention is to provide a new and improved match-package in which a number of matches can be carried conveniently with safety, and which is so constructed that the matches are automatically ignited by withdrawing them from the package.

In the accompanying drawings, Figure 1 is a side view of my improved match-package, parts being broken out. Fig. 2 is a horizontal sectional view on the line $x-x$, Fig. 1; and Fig. 3 is a vertical transverse sectional view on the line $y-y$, Fig. 1.

Similar letters of reference indicate corresponding parts.

The package A, which is made flat and of paper, is closed at the top and bottom, and is provided with a longitudinal partition, B, of pasteboard or wood, extending from the closed bottom to within a short distance of the top. The sides of said partition are beveled slightly toward each other at the lower end for the purpose of affording greater space in the lower part of the package for the heads of 25 the matches D. The sides of said partition are coated at the upper end with sand, emery, or roughened in any other suitable manner, so that when the matches are drawn out their heads are rubbed on said surface, and the 30 matches thus automatically ignited.

The package is provided a short distance from the upper end and in line with the upper edge of the partition B with a line, H, of perforations extending entirely around it, so 35 as to permit of tearing off the upper end, G,

from the package. The matches can then be seized and drawn out.

The package occupies very little space, as it is made flat, and can be conveniently carried in the vest-pocket with safety, as there 45 is no danger of the matches igniting except by being drawn out of the package.

I am aware that it is not broadly new to provide a package with a row of apertures to facilitate tearing; and I am also aware that 50 it is not broadly new to pack matches in a package at two sides of a partition in said package, and I do not claim these, broadly, as my invention.

Having thus described my invention, I claim 55 as new and desire to secure by Letters Patent—

A match-package composed of a flat paper casing provided with a longitudinal partition extending from one end to within a short distance of the other end, said partition having its faces roughened at the upper end of the package and its faces inclined toward each other at the lower end of the package, the casing having a line of perforations extending 60 around it at the top edge of the partition and 65 matches placed between the sides of the partition and the sides of the package, the heads of the matches being at the beveled end of the partition, substantially as herein shown and 70 described.

In testimony that I claim the foregoing as my invention I have signed my name in presence of subscribing witnesses.

FRANK SCHILZ.
